[57] CLAIM

The ornamental design for an eyeglass retainer, as shown and described.

DESCRIPTION

FIG. 1 is a perspective view of the eyeglass retainer showing my new design with the eyeglasses being shown in broken lines for illustrative purposes only; FIG. 2 is a side elevational view of one of the cloth members thereof, the annular connecting disk and matching cloth member being omitted for illustrative purposes only;

FIG. 3 is an enlarged end elevational view thereof looking from right to left in FIG. 2; and

FIG. 4 is an enlarged cross-sectional view of the annular disk portion thereof.

The portions of the claimed article which are not shown in FIGS. 3 and 4 have been omitted for ease of illustration only.
